[57] CLAIM

The ornamental design for an extrusion for ladder step, as shown and described.

DESCRIPTION

FIG. 1 is a perspective view of an extrusion for ladder step, embodying the present design;

FIG. 2 is an elevational view of the end opposite that seen in FIG. 1;

FIG. 3 is a plan view of the side seen in FIG. 1;

FIG. 4 is an elevational view of the edge seen in FIG. 1;

FIG. 5 is a plan view of the side opposite that seen in FIG. 1; and

FIG. 6 is an elevational view of the edge opposite that seen in FIG. 1.

The extrusion for ladder step has been broken away in the center in FIGS. 3, 4, 5 and 6 of the drawing for ease of illustration.
